Primary Examiner — Philip S Hyder*Assistant Examiner* — Darlington Ly*(74) Attorney, Agent, or Firm* — Leong C. Lei(57) **CLAIM**

The ornamental design for a screw tip protector set, as shown and described.

DESCRIPTION

FIG. 1 is a front perspective view of a screw tip protector set showing my new design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top plan view thereof; and,

FIG. 7 is a bottom plan view thereof.

The broken lines in the drawings illustrate portions of the screw tip protector set that forms no part of the claimed design.
